FURNACE CONSTRUCTION

John S. Wallis, Darien, and John W. Throckmorton, Wilton, Conn., assignors to Petro-Chem Development Company, New York, N. Y., a corporation of Delaware

Application November 2, 1942, Serial No. 464,210

4 Claims. (Cl. 122—510)

Our invention relates to improvements in tubular furnace construction.

The invention particularly resides in vertical tubular furnaces of the type used for heating fluids in distillation or cracking operations of hydrocarbon oils, in the heating of fluids in chemical processes or the generation of steam.

Furnaces of this type have a combustion chamber which encloses a bank of vertical heat exchange tubes. These tubes provide a continuous passage through the combustion chamber for fluid to be heated. Heating gases are supplied to the combustion chamber by burners arranged to distribute heat uniformly over the tubes within the furnace.

Solids in the fluid collect and harden on the internal surfaces of the tubes. The internal surfaces of the tubes are subject to corrosion or the accumulation of foreign substances separated from the fluids. The external surfaces of the tubes are also corroded or oxidized by the combustion gases. As a result, the tubes must be periodically cleaned and inspected, and repaired or replaced.

Two methods of positioning the tubes in the furnace have been employed, suspension of the tubes by their upper ends from the top of the combustion chamber, and supporting the tubes by their lower extremities on the bottom of the combustion chamber. If the tubes are suspended from their upper ends, it is necessary to reinforce the furnace to take care of the added weight. This expense and added weight is obviated if the tubes are supported at their lower ends. When supported at the bottom as in the De Florez Patent 1,989,612, dated January 29, 1935, it has been conventional practice to support the weight of the tubes on the lower tube sheet. This sheet is subjected to the heat of the furnace and must therefore have sufficient strength at the high temperatures existing to maintain the entire weight of the tube bank and its accessories. Difficulties are also experienced in inspection of the lower tube sheet and supports when the furnace is in operation.

We have devised a novel supporting structure for the tubes by which the weight of the tubes is carried by the lower supporting structure of the furnace, instead of the highly heated tube sheet. Furthermore, the supports upon which the tubes rest are located outside of the heating zone and are easily inspected since they are readily available and unaffected by the furnace heat.

An important object of our invention is the provision of a novel supporting structure for the

tubes of a tubular furnace by means of which the weight of the tubes is carried by the lower portion of the furnace supporting structure which positions the supports out of the heating zone.

Other objects and advantages of our invention will be apparent during the course of the following description.

In the drawing, forming a part of this specification and wherein like numerals are employed to designate like parts throughout the same,

Fig. 1 is a fragmentary lower portion of a tubular furnace showing my improved supporting structure for the tubes,

Fig. 2 is a transverse sectional view taken on the line 2—2 of Fig. 1,

Fig. 3 is a vertical sectional view taken on the line 3—3 of Fig. 2, and

Fig. 4 is a transverse sectional view taken on the line 4—4 of Fig. 1.

The furnace is carried upon supports 10. The fragmentary portion of the furnace shown in the drawing includes a cylindrical outer casing 11 lined with refractory 12, and a lower metallic tube sheet 13 protected with refractory 14.

Vertical heat exchange tubes 15 are disposed in a circle about the combustion chamber C and adjacent the wall of refractory 12. The tubes extend through refractory 14 and tube sheet 13 into an annular housing 16. The lower ends of tubes 15 are connected by return bend headers 17. As shown in Fig. 3, each header supports two of the tubes. A plug 18 below each of the tubes 15 is removable for purposes of cleaning and inspection. Lugs 19 on the headers 17 rest upon brackets 20 projecting from the walls of housing 16. Hinged doors 16a in the bottom of housing 16, below headers 17, permit ready access to the headers for removal of plugs 18 and inspection of the tube supporting means 19 and 20.

By providing the supporting means on the headers 17, the tube supporting structure, including both the lugs on the tubes and brackets on the furnace supports, are located out of the heating zone. Also, the doors 16a provide easy access to the supporting structure.

A further advantage of locating the supporting means on the header is the elimination of machining or welding the exterior surface of the tubes themselves. Where a tube has been machined or welded, the tube abutting is weakened and is more likely to rupture or to be distorted by heat and excessive stress imposed thereon for any cause. By attaching or affixing the supporting means to the header, these difficulties are eliminated.

It may thus be seen that we have accomplished the objects of our invention. We have provided a supporting structure for the vertical tubes 15 by means of which the weight of the tubes is carried by the lower supporting structure of the furnace. The tube supporting structure is positioned out of the heating zone and where it can be easily inspected at all times.

It is to be understood that the form of the invention herewith shown and described is to be taken as a preferred example and that various changes in the size, shape, and arrangement of parts may be resorted to without departing from the spirit of our invention or the scope of the appended claims.

Having thus described our invention, we claim:

1. Supports for vertical heat exchange tubes whose extremities extend outside the heating chamber of a furnace structure and are connected by return bend headers, including support members on the headers and brackets mounted on the furnace supporting structure, said support members and brackets located outside the heating chamber and coacting to support the weight of the tube bank.

2. Supports for vertical heat exchange tubes whose extremities extend outside the heating chamber of a furnace structure and are connected by return bend headers, including support members on the headers and brackets mounted on the furnace supporting structure, said support members and brackets located outside the heating chamber and coacting to support the

weight of the tube bank, and a housing separate from the heating chamber enclosing the extending ends of the tubes and their supports.

3. Supports for vertical heat exchange tubes whose extremities extend outside the heating chamber of a furnace structure and are connected by return bend headers, including support members on the headers and brackets mounted on the furnace supporting structure, said support members and brackets located outside the heating chamber and coacting to support the weight of the tube bank, and a housing insulated from the heating chamber enclosing the extending ends of the tubes and their supports, said housing having openings permitting ready access to the headers and supports.

4. Supports for vertical heat exchange tubes whose extremities extend outside the heating chamber of a furnace structure and are connected by return bend headers, including support members on the headers and brackets mounted on the furnace supporting structure, said support members and brackets located outside the heating chamber and coacting to support the weight of the tube bank, a housing insulated from the heating chamber enclosing the extending ends of the tubes and their supports, said housing having openings permitting ready access to the headers and supports, and cover plates for the housing openings.
